UNITED STATES PATENT OFFICE.

BENJAMIN P. VICKERY, OF BRADLEY, ILLINOIS, ASSIGNOR OF ONE-HALF TO ELMER E. PERKINS, OF CHICAGO, ILLINOIS.

TARGET TRAP.

Application filed October 17, 1921. Serial No. 503,241.

To all whom it may concern:

Be it known that I, BENJAMIN P. VICKERY, a citizen of the United States, residing at Bradley, in the county of Kankakee and State of Illinois, have invented certain new and useful Improvements in Target Traps, of which the following is a specification.

This invention relates to target traps of the type employed for throwing or projecting flying targets, commonly known as clay pigeons for trap shooting. One of the primary purposes of my invention is to provide a trap which will be simple in construction, easy to manipulate, one which will not be liable to get out of order, one which will be accurate and reliable in operation, and one which will be capable of the various adjustments requisite to give the targets the various desirable directions of flight.

Another object of my invention is to provide a target trap in which but one operating lever or instrumentality is necessary for manipulating the trap, this lever being adapted to control mechanism which not only restores the throwing arm to set position, but also retains it in this position, manipulation of the lever in one direction being adapted to restore the arm and in the opposite direction to release the arm permitting the throwing operation to take place.

Other objects and advantages of my invention should be readily appreciated as the same becomes better understood by reference to the following description, when considered in connection with the accompanying drawings.

Referring to the drawings—

Fig. 1 is a plan view of a target trap embodying my invention;

Fig. 2 is a similar view showing the throwing arm in set position;

Fig. 3 is a side elevation of the trap shown in Fig. 1;

Fig. 4 is a sectional detail view on the line 4—4 of Fig. 5;

Fig. 5 is a longitudinal sectional view;

Fig. 6 is a sectional view on the line 6—6 of Fig. 1;

Fig. 7 is a fragmentary sectional view on the line 7—7 of Fig. 3;

Fig. 8 is an enlarged plan view of the

target holding devices with the targets in position therein;

Fig. 9 is a side view; and

Fig. 10 is a view of one of the target holding devices in open position for the reception of a target.

Referring now to the drawings more in detail, reference character 11 indicates generally a base or platform of suitable construction upon which the operating mechanism is mounted, this base being preferably equipped with bearings to accommodate the sliding rod 12 connected at its rear end to an operating lever (not shown) by which the trap is manipulated. The base 11 is provided with a bearing opening 13 adapted to receive the center column 14 of a bifurcated standard 15, that portion of the standard which rests upon the base being provided with a circumferential flange 16 over which is disposed an arcuate plate or strap 17 of metal secured to the base 11 by a plurality of bolts 18, this strap serving to securely lock the standard to the base and at the same time permit of rotative movements of the standard relatively upon the base.

Upon the standard 15 there is fulcrumed upon the horizontally disposed bolts 19 a frame 21 bifurcated as shown in Figs. 1 and 2, the rear end of the frame being equipped with a handle 22 by which the frame and standard may be swung in the bearing opening 13 to vary the direction of flight of the targets from the trap, and forwardly of this handle the frame is equipped with depending lugs 23 to which a link 24 is connected, the lower end of the link being equipped with a member 25 comprising a horizontal portion 26 adapted to rest upon a horizontally slotted arm 27 extending rearwardly from the standard. A bolt 28 extending through the slot in the arm and through the portion 26 of the member 25 serves to lock this member in any position to which it may be adjusted longitudinally of the arm 27, and it will be manifest that by adjusting the member 25 inwardly or outwardly of the arm, the height of the rear end of the frame 21 may be adjusted so that the height of flight of the targets from the trap may be regulated at will. The arm 27 rests upon or extends in proximity to a rib 29 formed

upon the upper face of the base 11, and this rib is provided at intervals with openings 31 adapted to receive removable pins 32, by which the arm is locked in any position to which it may be adjusted relatively to the base. It will be manifest, therefore, that provision is made for varying both the horizontal and vertical directions of flight of the targets from the trap.

On the forward end of the frame 21 there is fulcrumed upon a bolt 33 a re-setting or restoring lever 34, and above this lever and rotatably mounted upon the same bolt 33 there is disposed the hub 35 which carries the throwing arm 36. This hub is shaped on its periphery to provide a notch 37, and upon the restoring lever 34 there is pivotally mounted a dog 38 which is urged toward and into engagement with this notch 37 by a spring 39 attached at one end to the dog and at its other end to an eye 41 carried by the outer end of the arm 34. The restoring arm 34 is normally held in the position shown in Fig. 1 by a tractile spring 42 attached at one end to the lever arm 34 and at its opposite end to an eye 43 near the rear end of the frame 21. The lever 34 is swung from the position shown in Fig. 1 to that shown in Fig. 2 by means of a chain 44 attached at one end to the eye 41, and trained over pulleys 45 and 46 mounted respectively on the frame 21 and the base 11, the opposite end of the chain being connected through an eye 47 to the operating rod 12 slidably mounted in the base. Rearward movement of this rod will exert a pull upon the chain which will swing the lever 34 into the position shown in Fig. 2, and when pull upon the chain is released, this lever will be restored to the normal position shown in Fig. 1 by the spring 42. When this lever is swung in a clockwise direction, into the position shown in Fig. 2, the dog 38 acting against the base of the notch 37 on the throwing arm hub 35 will rotate this hub so as to swing the throwing arm into the set position shown in Fig. 2.

The hub 35 is equipped with a short arm 48 disposed at an angle of 180° with respect to the arm 36, and a strong tractile spring 49 is attached through an eye 51 to this arm 48 and is equipped at its opposite end with a threaded rod 52 extending through an opening in an upright 53 projecting from the frame 21, tension upon the spring 49 being regulated by means of a nut 54 threaded into the rod 52 and preferably equipped with a crank handle 55 by means of which the nut may be rotated to increase or diminish the tension, as occasion requires.

When the arm is in the set position shown in Fig. 2, obviously the spring 49 is extended and under tension. When the arm is re-

leased, as will be later explained, this spring 65 swings the arm in a clockwise direction, viewing Fig. 2, and the momentum thereof is sufficient to carry the arm through an arc considerably in excess of 180° , so that it will be disposed over a ratchet tooth bar 56 carried by a pair of arms 57 projecting from the frame 21. For the purpose of holding the arm in the extreme position to which it swings during the throwing action and to prevent reverse movement thereof, I have mounted upon the throwing arm, in radial alignment with the ratchet bar 56, a channel shaped latch 58 provided with long and short depending tails 59 and 61, respectively, which are adapted to engage 80 with the ratchet teeth as shown in Fig. 7. An expansion spring 62 disposed between the latch 58 and the head of a bolt 63, extending through the latch and threaded into the arm 36, yieldingly urges the latch into 85 engagement with the ratchet bar so that the throwing arm is thereby automatically locked against reverse movement. Obviously, however, the construction of the latch and the ratchet teeth will permit further 90 swinging movement of the arm in a clockwise direction into set position.

For the purpose of locking the arm in set position, I have fulcrumed upon a supporting arm 64 carried by the frame 21, in a 95 plane between the restoring lever 34 and the throwing arm 36, a latch or lever 65, which is normally held with its upper end 66 beneath the path of travel of the throwing arm 36 by means of a tractile spring 67 attached at one end to the tail of the member 65 and at its other end to one of the arms 57. That portion of the member 65 beneath its fulcrum is manifestly disposed in the path of travel of the restoring lever 34 and when this lever is moved, through the instrumentality of the chain 44, from the position shown in Fig. 1 to that shown in Fig. 2, it engages the member 65 and swings it in a clockwise direction upon its fulcrum, 100 so as to dispose its upper end 66 in the path of the throwing arm 36, which is thereby held against swinging movement in a clockwise direction beyond the set position in which it is shown in Fig. 2. The throwing arm is also held against reverse movement by the dog 38 carried upon the restoring lever 34 and so long as tension is exerted upon the chain 44, the throwing arm will be held against movement in either direction. 105 The throwing arm when in set position is slightly beyond dead center, and when tension on the chain 44 is released the restoring lever 34 will be returned to normal position by the spring 42, and as soon as this 110 lever is withdrawn from engagement with the member 65, this member will be swung by its spring 67 so as to withdraw the upper

end 66 from the path of the throwing arm, thus permitting this arm to swing in a clockwise direction under the influence of the strong spring 49, thus causing the projection 5 of the target from the throwing arm which continues its movement under its own momentum, until its assumes a position over the ratchet bar 56 where it is held against reverse movement by the latch 58.

10 While in this position the arm is reloaded with one or more targets, whereupon the arm is moved to set position by a rearward pull upon the rod 12.

In trap shooting it is sometimes desirable 15 to discharge two targets simultaneously from the trap, and sometimes one, and therefore I have shown in this instance an arm equipped with a plurality of target holding devices so that two targets may be discharged if desired, and if only one target is desired, but one of the devices need be loaded. 20 In order to accommodate a plurality of targets, the arm 36 is forked at its outer end providing two termini 68 and 69, each having fixedly secured to its outer end a plate 71. Since the two holding devices are in all respects similar, but one of them will be described in detail. The two plates 71 are 25 preferably, for purposes of rigidity, connected together by one or more brace members 72.

Each plate 71 is shaped so as to provide a stationary finger 73 having undereut 30 guide-ways 74 adapted to receive one edge 35 of a target 75, the lower wall 76 of the groove being extended inwardly so as to afford an adequate support for the target. Upon the plate 71 the other movable finger 40 77 is pivoted at 78, the inner end of the finger 77 being disposed beneath the plate as shown. A tractile spring 79 tends to normally hold the pivoted finger in the 45 closed position shown in Fig. 8, thereby holding the target 75 in place by means of a roller 81, preferably of rubber or other suitable material, carried near the outer extremity of the pivoted finger 77. When 50 during the throwing movement of the arm, the centrifugal force exerted upon the target 75 exceeds the strength of the spring 79, the target will be forced outwardly and delivered from between the fingers, the pivoted finger 77 being moved by the ejection 55 of the target from the position shown in Fig. 8 to that shown in Fig. 10.

For the purposes of holding this pivoted finger in its open position, shown in Fig. 10, so that another target can be readily introduced between the fingers in the 60 reloading operation, I have pivotally mounted upon the finger 77 upon a pin 82 a cam-shaped latch 83 having a face 84 disposed further from the pivot pin 82 than the face 85. A tractile spring 86 attached at one

end to the latch and at its other to the plate 65 71 swings the latch, when the finger 77 is in open position, from the position shown in Fig. 8 to that shown in Fig. 10, thereby bringing the face 84 into engagement with the edge of the plate 71 so as to lock the 70 finger 77 in open position. When in the reloading operation a target is introduced between the fingers, its inner edge engages a tail 87 projecting from the latch 83 between the fingers and as the target is forced 75 inwardly into position it swings the tail 87 inwardly, thus releasing the latch so as to permit the pivoted finger to close into the position shown in Fig. 8 under the influence of the spring 79. It will be manifest therefore 80 that by holding the pivoted finger open so that it offers no resistance to the introduction of a target between the fingers, the ease and rapidity with which the loading operation may be performed is 85 greatly increased, and since the spring 86 is relatively light, the tail 87 offers but slight resistance to the positioning of the target in the hand.

It is believed that my invention, its construction, mode of operation and many of its inherent advantages will be understood from the foregoing without further description, and while I have shown and described a preferred embodiment, obviously 90 the details of construction are capable of considerable modification and variation without departing from the essence of the invention as defined in the following claims.

I claim:

1. In a target trap the combination of 100 a rotatable hub, a spring attached to one side thereof, a throwing arm projecting from the opposite side of said hub, an oscillatable lever pivoted concentrically with the hub, a dog carried by said lever in position to engage a notch in said hub, manual means for actuating said lever in one direction, a spring connected to said lever for moving the same in the opposite direction, 110 and a stop pivoted on a fulcrum between the planes of movement of said lever and said arm, the tail of said stop being disposed directly in the path of travel of said lever, whereby the stop is swung on its fulcrum to dispose the other end thereof in the path of said arm for holding the arm 115 against movement beyond set position.

2. In a target trap, the combination of 120 a rotatably mounted throwing arm, ratchet teeth disposed in proximity to the path of travel of said arm, a channel shaped pawl straddling said arm and projecting beneath the arm in position to engage said ratchet teeth, and a spring for urging said 125 pawl into engagement with said ratchet teeth whereby reverse movement of said arm is precluded.

3. In a target trap, the combination of a frame, a restoring lever fulcrumed thereon, a throwing arm rotatably mounted above and concentrically with said restoring lever, and an operative connection between said lever and said arm, means for actuating said lever and a stop fulcrumed in a plane between

said lever and said arm, the tail of said stop being disposed directly in the path of movement of said arm, whereby said stop is moved to dispose its upper end in the path of said arm to hold the arm in set position.

BENJAMIN P. VICKERY.
